(57) **CLAIM**

The ornamental design for a shoulder weight supporting harness, as shown and described.

DESCRIPTION

FIG. 1 is a front perspective view of a shoulder weight supporting harness showing our new design;

FIG. 2 is a rear elevation thereof;

FIG. 3 is a side elevation as seen from the left side of FIG. 1;

FIG. 4 is a side elevation as seen from the right side of FIG. 1;

FIG. 5 is a top plan view thereof; and,

FIG. 6 is a bottom plan view thereof.

The broken lines shown on the shoulder weight supporting harness represent stitching.
